UNITED STATES PATENT OFFICE.

ROY A. HOUDYSHELL, OF TAMA, IOWA, ASSIGNOR OF ONE-HALF TO CARL WESLEY
HOUDYSHELL, OF TAMA, IOWA.

PACKAGE-TIE.

1,181,767.

Specification of Letters Patent. Patented May 2, 1916.

Application filed April 24, 1915. Serial No. 23,676.

To all whom it may concern:

Be it known that I, Roy A. HOUDYSHELL, a citizen of the United States, residing at Tama, in the county of Tama and State of Iowa, have invented certain new and useful Improvements in Package-Ties; and I do hereby declare the following to be a full, clear, and exact description of the invention, such as will enable others skilled in the art 10 to which it appertains to make and use the same.

This invention relates to new and useful improvements in package ties and has for its principal object to provide a device which 15 may be constructed of a single piece of wire and which is capable of effectively holding a package particularly for use in postoffices and the like wherein it is desired to tie a number of letters into a single package.

20 Another object of the invention is to provide a device which is formed of resilient wire so that a loop of flexible material may be used and the package will be held under tension.

25 A further object of the invention is to provide a device which depends partly on the elasticity of the package being tied.

Still another object of the invention is to provide a package tie where the same string 30 may be used until the same is entirely worn out.

A still further object of the invention is to provide a package tie which is useful on packages of both large and small sizes, as 35 the string used on a large package may be used for a small package by turning the tie over and over until the string is drawn taut, thereby avoiding the necessity of providing strings of different sizes.

40 With these and other objects in view, the invention consists in the novel combination and arrangement of parts which will be fully set forth in the following specification and accompanying drawings, in which:

45 Figure 1 is a perspective view of a package of letters showing the same bound together with my improved package tie applied thereto, and Fig. 2 is a plan view of the package tie.

50 Referring now to the drawings by characters of reference, the numeral 1 designates the main bar of the device which is formed of a single piece of wire and bent outwardly at each end as at 2. Each of these outwardly 55 bent portions terminates in a loop 3, which

terminates in an inwardly bent portion 4 which projects to a point within close proximity to the bar 1 but is spaced slightly therefrom as illustrated in the drawing. The terminal of the inclined portion 4 terminates in the curved portions 5 and these curved portions are provided with the parallel extensions 6 which project perpendicular to the bar 1 hereinbefore referred to. Each of these parallel extensions 6 is bent 60 outwardly as at 7 and each of the outwardly bent portions terminates in the inclined portions 8 which in turn are provided with the loops 9 and the opposite ends of these loops terminate in the outwardly bent portions 10 65 which are bent angularly and intertwined so that the intertwined portions 11 lie parallel with the bar 1.

It will be evident from the foregoing that the main body of the device comprises the 70 bars 1, 6 and the intertwined portions 11 and this body is provided with the outwardly extending hook members designated generally by the numeral 12 which are formed at each corner. These hook members 75 are resilient due to the fact that the bent portions 5 and 7 are spaced from the bars 1 and the twisted portion 11 and it will thus be seen that the device is provided with a limited amount of resiliency. 80

In use it will be apparent that the cord by which the package is tied is first cut the desired length and the ends are then tied together, thus forming a loop. The same is then hooked over the package tie so that the 85 loop will overlie the body and project underneath of the hooks 12 whereupon the opposite end of the loop of cord is passed around the package and is then hooked over the co-operating hooks 12 on the opposite 90 side of the package tie as shown in Fig. 1. It will thus be seen that the package will be firmly clamped and the device may be readily tied due to the resilient nature in 95 its structure and also due to the fact that the package being tied is more or less resilient, thereby permitting the loop to be slipped over the hooks when the package is compressed. In this way it will be seen 100 that as soon as the package returns to its normal condition, the string will be taut and thereby firmly bind the several parts of the package together.

While in the foregoing there has been 105 shown and described the preferred embodiment

ment of this invention, it is to be understood that such changes may be made in the combination and arrangement of parts as will fall within the spirit and scope of the appended claims.

What is claimed is:

1. A package tie of the character described comprising a body, said body being formed of three coöperating bars of resilient wire and an intertwined portion of said wire, hooks formed at the four corners of the body, the longitudinal axes of the hooks lying in parallel relation and reduced portions connecting the hooks with the body.
2. A package tie of the character described including a bar, loops at the ends of the bar, inwardly inclined portions at

the terminals of the loops, bent portions at the terminals of the inwardly inclined portions, a pair of parallel bars at the ends of the bent portions, said bars extending perpendicularly to the first mentioned bar, bent portions at the terminals of the parallel bars, inwardly inclined portions at the ends of the bent portions, loops at the ends of the inwardly inclined portions, bent back portions at the ends of the loops, said bent back portions projecting toward each other and being intertwined.

In testimony whereof I affix my signature in presence of two witnesses.

ROY A. HOUDYSHELL.
